CLAIM

The ornamental design for a connector with pins and flange, as shown and described.

DESCRIPTION

FIG. 1 is a front, top and left side perspective view of a connector with pins and flange showing our new design.

FIG. 2 is a front elevation view thereof.

FIG. 3 is a rear elevation view thereof.

FIG. 4 is a left side elevation view thereof.

FIG. 5 is a right side view thereof.

FIG. 6 is a top view thereof; and,

FIG. 7 is a bottom view thereof.

The broken line portion in the drawing views is included to show unclaimed subject matter only and forms no part of the claimed design.
